UNITED STATES PATENT OFFICE.

GUSTAVE A. OVERSTROM, OF PASADENA, CALIFORNIA.

SCREEN.

Original application filed September 28, 1920, Serial No. 413,376. Divided and this application filed
March 30, 1925. Serial No. 19,201.

My invention relates particularly to screens where a very high frequency of vibration is employed to accomplish the desired results.

5 This application is a division of my application Serial No. 413,376, filed September 28, 1920, for vibrating screens, and relates particularly to means for fastening and holding the screening cloth securely in place and 10 wherein the screening cloth is quickly and easily replaced.

Other objects will appear hereinafter and I attain these objects by the construction illustrated in the accompanying drawing in 15 which:

Figure 1 is a cross section of a portion of a screen box illustrating the principles of my invention as applied to the stretching and fastening of the screen cloth.

20 Fig. 2 is a sectional view in detail showing a method of fastening fine screen cloth to the stretching beams.

Fig. 3 is a cross sectional view of a part of a screen box illustrating another mode of 25 stretching and fastening the screening cloth.

Fig. 4 is a transverse section taken near one end of the screen box.

The same numerals refer to like parts throughout the several views.

30 In the operation of vibrating screens, I have found that the longest life of the screen cloth, as well as the greatest capacity per square foot of screening surface and the least blinding of the screens is obtained when the 35 screen cloth is stretched tight between the sides of a vibrating box, and rigidly held to such box at the sides and ends only, allowing a clear unobstructed flow over the screening surface without bolts, rivets or other obstructions 40 to hold the screen cloth to the vibrating member.

I have found also that where the sides of the screen cloth were rigidly held to a stationary frame, and the central part of the 45 wire screen cloth was attached to a vibrating member, not alone did the wires soon break near the vibrating connection bolts, but the whole screen cloth wore rapidly where the wires were in contact with each other. Undoubtedly this was caused by the mechanical 50 wrecking action and abrasion due to the distortion of the position of the wires.

I therefore naturally reached the conclusion 55 that the wires comprising the cloth must not be disturbed in relation to each other, but

must move in unison throughout the width and length of the screen cloth, and that the screen cloth should not be fastened to the vibrating member anywhere on the screening surface. Longitudinal connections to the center of the screen cloth prevented the even distribution of the material to be screened, especially if the feed did not land exactly uniformly each side of such connections.

As a general rule, I operate my screens 65 from 1500 to 2000 vibrations per minute, and the vibrations may be about 1/16-inch diameter on fine material, 1/8-inch on medium size and 3/16-inch or slightly over on coarse as well as on moist material, on which less number of vibrations and greater movement gives better results.

To effectively meet these and various other conditions under which the screening operations are conducted and to permit ready replacement of the worn-out screens, I provide the construction herein disclosed. My invention accordingly includes special fastening devices which are capable of being variously utilized. As a specific example, however, 75 illustrative of the principles of my invention applied to a screen box which fulfills the above and other conditions, the screen box is made up of sides 1, to which are attached the top rails 2 and the bottom rails 3 provided 80 with tie rods 7 on which are pipe struts 8 to hold the sides securely braced. The frame is held together by nuts 9 on the ends of rods 7. The end ties 5 and 6 hold the sides 1 and the tie pieces firmly together. The supporting pipe 12 is held by clamps 11 and collars 13 are shrunk onto pipe 12. To the ends of pipe 12 are pressed spiral springs 14, which are held in place by check nuts 15 on the ends of pipe 12. The spiral springs 14 are clamped 85 fast in the spring clamps 16 which are rigidly secured onto the stationary beams 18.

The screen cloth 52 is fastened to stretching beams 53. Stretching bolts 54 serve to draw the beams 53 toward the sides 1 or bottom rail 3, thereby pulling the screen cloth 100 drum tight.

In cases where wood is desirable for stretching beams, the construction shown in Fig. 4 is used. The edges of the screen cloth are turned at right angles and the cloth held between cleats 55 and stretching beams 53, the cleats being screwed on to the beams, thereby clamping the cloth between the two. The turned sides of the cloth are also tacked 110

to stretching beams 53 in case of the finer cloth.

For stretching coarser and heavier cloth, steel channels and angles are more frequently used, as shown in detail in Figs. 1, 2 and 3. In the upper part of Fig. 1 and in the lower part of Fig. 3 I have shown independent wire stretchers, and in the lower part of Fig. 1 and the upper part of Fig. 3, I have shown 10 twin stretchers for stretching, respectively, a single screen or double screens. In case of independent stretchers a single spacer 56 may be used. When the channels are used, they themselves form spacers.

15 Inside liners 57 serve to protect the sides 1 from wear, and also to hold down solidly the stretching beams 53 to the bottom rails 3. The wedges 58 which bear against the top rails 2, serve to press down the liners 57. 20 The wedges are not driven home solidly until the screen cloth is stretched.

When heavy screen cloth is used, it is only necessary to bend the sides of the cloth over double or U-shaped, then slip the U over the 25 flange of the channel or angle. When lighter cloth is used, I employ one or two U clips, one 59 fitting inside the other 60, outside of the U-shaped side of the screen cloth. This method effectually prevents slipping of the 30 screen cloth when stretching, but also allows of easily slipping the flimsy screen cloth into place without removing the stretching beams from the screen box. In case of very fine bronze and brass screens, I sometimes only 35 use the inside U clip and solder screen cloth 52 to the inside U clip 59 as shown at 61, Fig. 2.

Where twin stretching is used in triple deck screens with sizes in tandem or more as shown in diagram, Fig. 1, the cloths cannot be slipped in when stretching beams are in position, but the screens must be put on to the beams outside the box and then dropped in place. In that case a nut 62 is riveted or welded to beams 53 and a tap bolt 63 employed for stretching. It would be impossible to put in bolts 54 in such a situation. 40 45

Having set forth the object and nature of my invention and various constructions embodying the principles thereof, what I claim 50 as new and useful and of my own invention and desire to secure by Letters Patent, is:

1. In vibrator structures, a screen box, a plurality of U-beams extending longitudinally of said box, screen cloths overlapping the edges of said beams and means for drawing said beam toward the sides of said box to draw said cloths taut, the width of said means forming means for accurately spacing the cloths. 55 60

2. In a vibrator structure, a screen box having beams extending longitudinally thereof near the top and bottom, flanged beams extending parallel to said beams, screen cloths overlapping said flanged beams and means connected to said flanged beams 65 for drawing said cloths tight, the width of said means forming means for accurately spacing the cloths.

In testimony whereof I have hereunto set 70 my hand on this fourth day of March, A. D. 1925.

GUSTAVE A. OVERSTROM.
